SPINNING TOP DEVICE

James M. McBride, Crab Orchard, Tenn.

Application April 26, 1954, Serial No. 30,188

Term of patent 7 years

(Cl. D34—15)

FIG. 1

FIG. 2

To all whom it may concern:

Be it known that I, James M. McBride, a citizen of the United States of America; residing at Crab Orchard, in the county of Cumberland and State of Tennessee, have invented a new, original, and ornamental Design for a Spinning Top Device, of which the following is a specification, reference being had to the accompanying drawing, forming a part thereof, in which

Figure 1 is a perspective view of a spinning top device, showing my new design; and

Fig. 2 is a perspective view taken from a different angle.

The characteristic or dominant features of the design are shown by means of full lines in the drawing.

I claim:

The ornamental design for a spinning top device, as shown and described.
